John Gardiner

United States Patent Office.

JOHN GARDINER, OF PHILADELPHIA, PENNSYLVANIA.

Letters Patent No. 97,070, dated November 23, 1869.

IMPROVEMENT IN GRAIN-CONVEYERS.

The Schedule referred to in these Letters Patent and making part of the same.

To all whom it may concern:

Be it known that I, JOHN GARDINER, of the city and county of Philadelphia, State of Pennsylvania, have invented a new and useful Improvement in Grain-Conveyers; and I do hereby declare that the following is a full, clear, and exact description of the construction and operation of the same, reference being had to the annexed drawings.

Figure 1 is a side elevation, with the unloading-apparatus, fig. 3, and the brushing-apparatus, fig. 5, attached.

Figure 2 is an end view of the same.

Figure 3 is a side view of the unloading-apparatus.

Figure 4 is an end view of the same.

Figure 5 is a side view of the brushing-apparatus in position on fig. 1.

Figure 6 is an end view of the same in position on fig. 2.

Figure 7 is a top view of one of the bows or stretchers.

Figure 8 is a side view of the same, with a section enlarged, showing a lip or projection on the end.

Figures 9 and 10 are top and edge views of one of the hinged bases of the bows.

Like letters in all the figures indicate the same parts.

The nature of my invention mainly consists in constructing and combining, with the usual canvas grain-conveyer, a carriage provided with adjustable arms supporting pulleys, with a semicircular face operating beneath the upper section of the conveyer, for the purpose of unloading the same at any point between the two ends.

Also, in combining with conveyer, a carriage provided with rotating brushes operating above the upper section of the conveyer, and immediately over the unloading apparatus, for the purpose of removing any grain that may adhere to the canvas when discharging.

Also, in constructing the bows or stretcher with a small projection on each end, and with hinged bases, and attaching the same to the upper surfaces of the belts, instead of the under surfaces, as is now the case.

To enable others skilled in the art to make and use my invention, I will proceed to describe its construction and operation.

I use the ordinary conveyer now in use, constructed by attaching a strip of canvas, or other flexible material, to the upper surfaces and inner edges of two parallel belts, and placing the same over four suitable pulleys attached to two horizontal shafts, two pulleys on each shaft.

The shafts are parallel with each other, and placed at such a distance apart as will be equal to the intended length of the conveyer.

The pulleys are set on the shafts at such a distance

apart as will allow the canvas, when the belts are placed upon them, to be suspended loosely between the belts, forming a bag or apron, which receives the grain in a continuous stream, carries it to the extreme end, and discharges it only at that point.

The belts are kept in position by strips of metal attached to their under surfaces.

The strips are straight at each end equal to the width of the belts; then bend in the form of a bow, and extend low enough to clear the canvas bag.

I construct the conveyer with two tram-ways A A, fig. 1, running the whole length of the conveyer. One tram-way, is on a line with the lower section of the belts, for the purpose of supporting and shifting with facility the carriage, fig. 3, for unloading the conveyer at any desired point. The other tram-way is above the upper section of the belts, for supporting and shifting the carriage, fig. 5, for brushing.

I also use the tram-ways for supporting the carrier-pulleys necessary for supporting both the upper and lower sections of the belts.

Fig. 3, B is a carriage, with flanged wheels to guide it on the tram-way, supporting the adjustable arms C C and reversing or unloading pulleys D D.

Attached to the pivot end of the adjustable arms C C, either between the bearings or to the pivot outside of the bearing are wheels E E, having their circumferences cut with a screw-thread, one right and the other left-hand.

Operating the screw-wheels, is the shaft F, for the purpose of elevating the pulleys D D, when in action, or depressing, when desired.

Attached to the carriage B, on both sides, are the chutes G G, placed at such an angle as will permit the grain, when thrown upon them, to pass freely into the bins.

The upper edge of the chutes extends up under the belts and projects, at the lower edge, beyond the carriage, to prevent the grain from falling on to the under section of the belts as they pass under the carriage, or on to the tram-way.

Owing to the roughness of some grain, some of it adheres to the canvas and is scattered and mixed with other grain.

To obviate this, I combine, with the upper section of the conveyer, a pair of rotating brushes, H H, suspended from underneath the carriage B, fig. 5, by suitable hangers.

The brushes are arranged at an angle coincident with the angle the canvas assumes when the unloading-apparatus is in action, and also arranged at an angle tending backward from the point of intersection of their centre lines from thirty to forty-five degrees, and are in contact with the canvas only when the unloading-apparatus is in action.

The rotating brushes H H are connected with each

other, and with a horizontal shaft, I, (attached to the carriage B,) by suitable gearing, and driven by the endless cord J, from the grooved pulleys K K, attached to the shafts at each end of the conveyer, that supports and moves the belts; thence, with one or more full turns around the flanged drum L, attached to the horizontal shaft I, thus affording a continuous motion to the rotating brushes, and permitting a change of position to the carriage on the tram-way without altering the adjustment of the endless cord.

I construct the bows M, fig. 6, with separate bases, N, and attach the bows to them in a position vertical to their plane, forming a hinge-joint, m n.

I attach the bows M in the same vertical position by their bases N to the upper surfaces of the belts by means of rivets, for the purpose of keeping the belts in a parallel position on their pulleys and preserving the under surfaces of the belts unobstructed for the perfect action of the unloading-apparatus, and also to freely permit the belts to change from a bevel to an angular position by the hinge-joints when the unloading-apparatus is in action.

As the weight of the grain in the bag would have a tendency to drag the belts from their pulleys, in consequence of the unrestrained action of the hinge-joints of the bows permitting the outside edges of the belts to tilt upward, I construct the bows M with a small projection, m, on each end, that bears firmly on the bases N and effectually preserves the belts in their proper bevel position.

In operating my improved grain-conveyer, the carriage, fig. 3, is to be run along the tram-way to the desired location. The adjustable arms are then to be elevated until the unloading pulleys reverse the bag, lifts the belts up from off the carrier-pulleys until their outer edges are depressed by their weight to the same angle the canvas assumes, which is readily per-

mitted by the hinge-joints of the bows. The carriage, fig. 5, is then to be placed over the pulleys of the unloading-apparatus.

The grain, as it approaches in the bag, is elevated to the desired point, when it will fall, by its own gravity, down the sides of the bag and belts on to the chutes and into the bins.

The rotating brushes being in motion, and in contact with the reversed bag, any grain that adheres to it is readily removed.

Having thus fully described my improvement in grain-conveyers,

What I claim therein as new, and desire to secure by Letters Patent, is—

1. The construction of the carriage B, fig. 3, with the adjustable arms C C and the unloading-pulleys D D, and their combination with the grain-conveyer, substantially in the manner herein described, and for the purpose set forth.

2. The use of the tram-ways A A, fig. 1, and the device for unloading the conveyer at any point intermediate between the two ends, either by reversing the bag or twisting the belts or bag, so as to unload the conveyer on either or both sides.

3. The construction of the bows M, with the projection m, the bases N, and the hinge-joint m n, and their attachment to the upper surfaces of the parallel belts of the grain-conveyer, substantially in the manner herein described, and for the purpose set forth.

4. The arrangement and combination of the rotating brushes H H with the grain-conveyer, substantially in the manner herein described, and for the purpose set forth.

JOHN GARDINER. [L. S.]
